W. MEYER

MAGNETIC HOLDER-ON

Filed April 16, 1920

Fig:2.

Inventor
Waldemar Meyer,
By his Attorney J. Wooster.

UNITED STATES PATENT OFFICE.

WALDEMAR MEYER, OF WOODHAVEN, NEW YORK.

MAGNETIC HOLDER-ON.

Application filed April 16, 1920. Serial No. 374,437.

To all whom it may concern:

Be it known that I, WALDEMAR MEYER, a citizen of the United States, and resident of Woodhaven, in the county of Queens and State of New York, have invented certain new and useful Magnetic Holder-Ons, of which the following is a specification.

This invention relates to holder-on, and has particular reference to the provision of a magnetically operated holder on for use in riveting, whereby the manual labor now required by a riveter is reduced, and better and more rapid work produced with a less skilled operator.

By this invention, the manual work of holding the tool to the work is largely done by a magnet without especial attention on the part of the operator, leaving him free to devote his entire attention to the accurate and tight setting of the rivet.

The invention comprises in combination with a rivet set, a magnet having a pole or poles disposed adjacent the set for holding to the work to preferably provide a three point engagement, with provision for relative movement of at least one so that flat, curved, or lapped work can be handled with one tool, with either automatic or simple hand adjustment to fit the contour of the work.

In the accompanying drawings,

Figure 1 is an elevation, partly in section of a preferred form.

Figure 2 is a bottom plan view.

1 represents a frame or bar of magnetizable material carrying a handle 2 fastened by nuts, and two cores 3, 3, having magnetizing windings 4. Each core 3 carries an adjustable headed plug 5, threaded therein, and between the plug head and the end of the core may be interposed backing washers 6, to adjust the plugs to the work, as lapped plates 7, 8.

9 is the holder having a heading recess for rivet 10. The shank of the set is reduced so as to reciprocate in socket 11 of bar 1. The shank passes through expansion spring 12 and is limited in one direction by the enlarged portion striking the bar 1, and adjustably in the opposite direction by the adjustment of nut 14 on threaded end 13. The yielding movement is very slight, and the spring cannot disengage the tool when the current is on, nor does the spring materially yield under the hammer blow.

The electric circuit is by wire 16 to switch

blade 17, by wire 18 through both coils 4 and may then be grounded on the handle, or may return by wire 19.

By the foregoing construction is provided a rivet holder-on comprising magnetic means for holding to the work and a holder for bearing on the rivet head. By adjustment of one or both core end plugs, it will be seen that close contact can be assured for varying character of work, and in the specific means for adjustment herein provided, the magnetic continuity between the core and the work, and between the core and the bar, is in no way impaired. For curved work, it may be desirable to use end plugs specially formed and adjusted to fit the particular contour so as to insure a good magnetic circuit without unnecessary air gaps.

In actual practice with this tool in setting a large number of rivets on various kinds of work a decided saving in time and effort has been obtained, as well as more regularly formed and tighter rivets than is obtained in ordinary practice with previous devices.

Various modifications and changes may be made in the specific details without departing from the scope of the appended claims.

What I claim is:

1. A holder-on comprising a bar, a plurality of electromagnets secured to the bar, a holder carried by the bar and adapted to engage a rivet head, and means between said electromagnets and the work for adjusting the distance between a magnet coil and the work to conform to the contour of the work.

2. A holder-on comprising in combination, a bar, a magnet secured thereto for cooperation with the work, a holder carried by the bar and adapted to engage a rivet head, and a plug removably secured to the magnet between it and the work to adjust the elevation between the ends of the holder and magnet to conform to the contour of the work.

3. In an electro-magnetic holder-on, a bar, a holder yieldingly supported by said bar, solenoids carried by said bar on each side of said holder a handle attached to the bar, and a control switch for the solenoids located on a side of said handle.

4. In an electro-magnetic holder-on, a bar, a holder carried by said bar, an electromagnet comprising a core carried by said bar, a coil on said core, and an adjustable pole piece in the end of said core.

5. In an electro-magnetic holder-on, a bar having an opening, a holder passing through said opening, a spring between said holder and said bar for holding the former against 5 the work, means on said bar for limiting the position assumed by said holder under the influence of said spring, and electro-magnetic means for holding the bar to the work.

6. A holder-on comprising a bar, an electromagnet secured thereto for cooperation with the work, a holder slideable through said bar, means on each side of the bar to limit the movement of the holder in either direction, and a yieldable means in cooperation 15 with said bar and holder to press the holder against the work.

7. A holder-on comprising a bar, a plurality of magnets secured to the bar, a handle also fastened to the bar, a holder slideable through the bar, and a clamping means securing both the handle and the magnet to the bar.

8. In a holder-on, the combination with a bar, of an electromagnet clamped to the 25 bar for cooperation with the work, the pole

piece of the magnet adjacent the work being provided with a plug removably threaded to an end portion of the magnet, and a backing washer placed between said magnet and plug.

9. In a holder-on, the combination with a plurality of spaced electromagnets for cooperation with the work, a bar adapted to form a part of the magnetic circuit to which said magnets are clamped to give a low reluctance to the magnetic circuit, means for varying the elevation of at least one of the magnets relative to the work, a holder slideable through the bar and provided with means for limiting the movement of the holder in either direction, a yieldable means in cooperation with said bar and holder to press the holder against the work, a handle secured to the bar, and a control switch for the magnets located adjacent the handle.

Signed at New York, in the county of New York and State of New York, this 3d day of April, A. D. 1920.

WALDEMAR MEYER.
